241,991

INVERTIBLE STOOL OR SIMILAR ARTICLE

Richard Lewis, 464 Green Bay Road,
Winnetka, Ill. 60093

Filed Jan. 8, 1975, Ser. No. 539,331

Term of patent 14 years

Int. Cl. D6—01

U.S. Cl. D6—3

FIG. 1

FIG. 2

FIG. 4

FIG. 3

FIG. 1 is a perspective view of an invertible stool or similar article embodying my new design.

FIG. 2 is an elevation thereof, all sides corresponding to that shown.

FIG. 3 is a plan view of a top or bottom end view thereof shown in FIGS. 1 and 2, the end shown serving alternately as the top or bottom of the chair.

FIG. 4 is a perspective view of another embodiment of the invertible stool or similar article.

I claim:

The ornamental design for an invertible stool or similar article, as shown and described.
